UNITED STATES PATENT OFFICE.

KINGSLEY HIGGINSON, OF LONDON, ENGLAND, ASSIGNOR TO CAREY-GAVEY SYNDICATE LIMITED, OF LONDON, ENGLAND, A BRITISH COMPANY.

FILM-FEED MECHANISM FOR CINEMATOGRAPHS.

Application filed May 9, 1923. Serial No. 637,802.

To all whom it may concern:

Be it known that I, KINGSLEY HIGGINSON, a subject of the King of England, residing in London, England, have invented certain new and useful Improvements in Film-Feed Mechanism for Cinematographs, of which the following is a specification.

This invention relates to film-feed mechanism of the accelerated Geneva stop-motion type for intermittently feeding the film of cinematographs and like apparatus, such for example as cinematographic cameras, wherein a rotary pin-carrier having its pins eccentric to its axis of rotation, is itself rotatable bodily about a second axis parallel to the said axis of rotation.

In this type of film-feed mechanism the actual speed of movement of the film through the gate of a cinematograph is increased beyond the speed due to the Maltese cross being driven by a pin travelling at a uniform speed round a circular path, and the duration of the period during which the film is in motion is considerably reduced and the duration of its stationary condition and therefore the illumination of the film is relatively increased.

This invention has for its main object to provide an improved construction of locking device for mechanism of the type referred to.

According to the present invention there is provided mechanism of the accelerated Geneva stop-motion type described, characterized by the provision of locking means so constructed and arranged that the cross remains locked thereby after a part of the pin has entered a slot and, after feed has taken place, is locked again before the pin has entirely left the same slot, the cross being always locked except when the pin is in driving engagement with it.

Conveniently, the main cross is formed or provided with a co-axial auxiliary cross rigidly connected with it, which auxiliary cross is held locked by a locking member immediately before and immediately after a feed movement whilst the main cross is otherwise interlocked.

In the accompanying drawings which il-

lustrate three methods of carrying the invention into effect—

Figure 1 illustrates one type of Geneva stop-motion device wherein the pin is rotatably mounted upon the locking-disc;

Figure 2 illustrates the device of Figure 1 wherein the cross is shown in the mid-position between two locking positions;

Figure 3 is a side elevation of the device shown in Figure 1.

Referring to the drawing, the locking-disc 1 is shown provided with a disc 2 rotatably mounted thereon and which is provided at its periphery with a pin 3. The axis of rotation of the disc 2 is parallel to the rotational axis of the disc 1. The disc 2 is geared to the locking-disc 1 in such a manner that as the same is rotated a circular path is traversed by the pin 3 relatively to the locking-disc 1, and the axis of rotation of the disc 2 is so situated relatively to the axis of rotation of the locking-disc 1 that during the rotation of the locking-disc the pin 3 crosses the periphery of the disc 1 every complete revolution of the pin, thereby causing the same to traverse what is known as a curtate epicycloidal path. The locking-disc 1 is provided with a cylindrical flange 4 which constitutes the locking surface for a Maltese cross 5. The disc 2 is carried by a spindle journaled in a boss 6 which projects from that face of the locking-disc 1 which is situated opposite to that which bears the locking-flange 4. The locking flange 4 is cut away for a portion 75 of its circumference to provide a slot 4^a to permit the pin 3 and the disc 2 to project beyond the circumference of the flange during their rotational movement. Upon that end of the spindle of the disc 2 which projects through the boss 6 in the disc 1 there is secured a pinion 7 arranged to engage with a stationary spur-wheel 8 mounted coaxially with the locking-disc 1. The ratio between the said pinion 7 and spur-wheel 8 80 may be varied according to the requirements desired, but in the specific example shown the ratio is 1:3.

With the arrangement hereinbefore described the pin 3 traverses a path which 100

closes itself at every revolution of the locking-disc. The cross 5 is of the usual four-slot type but of special design to facilitate the locking thereof. The slots are tangential each to the path of the pin 3 when this enters and leaves the same.

The cross 5 is shown with a portion of each of its corners turned off so as to form a second or auxiliary cross 9 integral with the main cross 5 and mounted on the same rotational axis, which auxiliary cross is arranged to engage with the surface of the flange 4 on the locking-disc 1 in the same manner as the cross itself engages with the said flange. The flange of the locking-disc is so slotted at 4^a as to permit the pin periodically to pass into and out of the circumference of the flange 4 but as the slot which permits of such a movement is of such a length as to also permit the cross 5 to rotate before the pin 3 has entered into engagement with a slot therein it is necessary to provide a second slot or recess 4^b in the periphery of the flange of the disc 25 which has to be so arranged as to permit the auxiliary cross 9, formed by the turned off portion of the main cross, to rotate only when the pin 3 is in engagement with a slot in the main cross 5.

Thus it will be seen in the construction hereinbefore described that when the locking-disc is rotated the pin 3 is rotated relatively thereto at three times the speed of the locking-disc such that when the pin 30 enters into a slot in the cross it will rotate the same at three times the speed of the locking-disc thus enabling the cross to be turned through one quarter of a revolution whilst the disc 1 is being rotated through 30°. The movement of the pin is such that at the moment of entry into a slot in the cross the slot is disposed tangentially to the path of the pin.

Further it will be seen that according to this construction the speed of the film is increased thereby increasing the period during which the film is illuminated and permitting, in the case of kinematographic projection, a further shutter blade to be inserted to obviate "flicker" and at the same time increase the illuminosity of the screen.

The Geneva stop-motion device hereinbefore referred to is preferably constructed to run in an oil bath thereby ensuring that the parts thereof rotate with the greatest ease.

Thus it will be appreciated that the described locking device owing to its precision renders film-feed mechanism of the Geneva stop-motion type particularly suitable both for kinematographic cameras and projection apparatus, wherein the time interval for the movement of the film through the gate is considerably reduced without altering the interval between successive move-

ments of the film, because the time interval during which the Maltese cross is free to move is reduced to a minimum.

I claim:

1. In cinematograph film-feed apparatus of the accelerated Geneva stop-motion type, the combination with a main rotary wheel of Maltese-cross pattern, a pin-carrier mounted to rotate about an axis of rotation parallel with the axis of rotation of said wheel and mounted to be given a rotary motion of translation about a second axis parallel with the axis of rotation of said wheel, and a pin mounted eccentrically on said pin-carrier and arranged to enter and leave slots in said wheel in succession and thereby impart intermittent angular feed movement to the wheel, of an auxiliary rotary wheel of Maltese-cross pattern rigidly connected coaxially with said main wheel, a rotary locking member arranged to lock and unlock both of said wheels at different times, the main wheel being unlocked and locked before the auxiliary wheel is respectively unlocked and locked during the same revolution, and means for rotating said auxiliary wheel and said locking member.

2. In cinematograph film-feed apparatus of the accelerated Geneva stop-motion type, the combination with a main rotary wheel of Maltese-cross pattern, and a driving pin mounted to be given a rotatory motion of translation about an axis parallel with the axis of rotation of said wheel and arranged to enter and leave slots in said wheel in succession and thereby impart intermittent angular feed movement to the wheel, of an auxiliary rotary wheel of the Maltese-cross pattern integral with said main wheel, a cylindrical rotary locking member arranged to co-act with the peripheries of said wheels and lock the same, but having a slot for receiving the ends of the arms of the main wheel and having a recess parallel with but shorter than said slot, which recess is arranged between the ends of said slot for receiving the ends of the arms of the auxiliary wheel, the portions of the periphery of the locking member at the ends of said recess being adapted to lock the auxiliary wheel whilst the main wheel is unlocked.

3. In cinematograph film-feed apparatus of the accelerated Geneva stop-motion type, the combination of a rotary wheel of Maltese-cross pattern, a pin-carrier mounted to rotate about an axis of rotation parallel with the axis of rotation of said wheel and mounted to be given a rotary motion of translation about a second axis parallel with the axis of rotation of said wheel, a pin mounted eccentrically on said pin carrier and arranged to enter and leave slots in said wheel in succession and thereby impart intermittent angular feed movement to the latter, and locking means arranged to lock

said wheel all the time except when the pin is in driving engagement with it, which locking means comprises two locking surfaces whereof the one ceases to be operative shortly before feed occurs and operates again shortly after feed has ceased, while the second is operative during two short periods of time, one ending immediately be-

fore feed commences, and the second commencing immediately after feed has taken place, while the first said locking means is inoperative, substantially as described.

In testimony whereof I affix my signature.

KINGSLEY HIGGINSON.
